His atty.

UNITED STATES PATENT OFFICE.

AUGUSTUS E. DONALDSON, OF TOLEDO, OHIO, ASSIGNOR TO THE BUNTING BRASS & BRONZE COMPANY, OF TOLEDO, OHIO, A CORPORATION OF OHIO.

END-TRIMMING MACHINE.

1,302,532.

Specification of Letters Patent.

Patented May 6, 1919.

Application filed June 26, 1917. Serial No. 177,069.

To all whom it may concern:

Be it known that I, AUGUSTUS E. DONALDSON, a citizen of the United States, and a resident of Toledo, in the county of Lucas and State of Ohio, have invented a certain new and useful End-Trimming Machine; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to means for broaching or trimming the ends of metal tubing, bars, or the like, and has for its object the provision of a simple and efficient means of this character which is capable of being easily and rapidly operable to simultaneously broach both ends of an article fed thereto.

A further object of my invention is the provision of improved means which is automatically operable to successively feed articles to the broaching or trimming means in proper timed relation to the operating of such means.

The invention is fully described in the following specification, and while, in its broader aspect, it is capable of embodiment in numerous forms, a preferred embodiment thereof is illustrated in the accompanying drawings, in which,

Figure 1 is a sectional elevation of a mechanism embodying the invention. Fig. 2 is a section thereof on the line 2-2 in Fig. 1, and Fig. 3 is a fragmentary plan view of the trimming die and holding means therefor.

Referring to the drawings, 1 designates the bed of a press with which my broaching or trimming means may be associated, and 2 a bolster plate mounted on said bed. A pair of die carrying plates 3-8, each with a foot flange 4 projecting outward therefrom are mounted on the bolster plate 2 for adjustment toward and away from each other, and are connected by right and left adjusting screws 5-6 to facilitate a simultaneous uniform adjustment thereof with respect to a common center line. Screws 6 under the

bolster plate 2 through slots 7 in the respective flanges 4 and clamp said flanges in adjusted position to the bolster plate.

Each plate 3 stands upright with a vertically extending recess 8 which has its upper end open and has a pair of die blocks 9-9 mounted therein. The die blocks 9-9 for each plate 3 are mounted in a common vertical plane which parallels the inner face of said plate and the inner or adjacent sides of such blocks are oppositely inclined to cooperate to form a V-shaped opening or notch 10 therebetween which is open at its top for a downward insertion of a work piece therein. The inner inclined wall of each die block is toothed or serrated to facilitate a broaching or trimming of the end of a work piece when forced down in the opening between the blocks as hereinafter described, while each die in the present instance comprises two parts it is evident that such parts may be made in a single piece if desired.

Work pieces *a* are carried in any desired number within an inclined chute or magazine 11 and fed by gravity therefrom into a horizontal way through which the work pieces are successively directed into position over the die openings 10. This way comprises the two side bars 12 of channel form with their channels facing each other and adapted to loosely receive the respective ends of a work piece, the upper flange of each bar being cut away in register with the chute 11 to permit the passage of work pieces from said chute into the way formed by the bars 12. The upper and lower flanges of the bars 12 are also cut away in the forward ends of said bars to render the forward end portions of said bars more flexible and to permit the vertical discharge of a work piece from between the bars when in register with the die openings 10. The forward ends of the bars 12-12 extend beyond the dies 9 and are connected by a bolt 13 on which is mounted a coiled compression spring 14 adapted to cooperate with said bolt to normally cause an inward flexing of the bar ends.

The inward yielding flexing of the forward ends of the bars 12 in this manner causes a work piece *a*, when moved therebetween in register with the die openings

10, to be frictionally engaged at its ends by said bars and supported in position over said die openings, as shown in Fig. 1.

The present ram 15 which is mounted for 5 vertical movement over the bed plate 2 carries a plunger member 16, which upon a downward movement thereof coacts at its lower end with a work piece *a*, held by the bars 12 over the die openings 10, and forces 10 the work piece down between the sets of dies 9, its ends being broached or trimmed during such downward movements by reason of the coaction of the serrated die surfaces therewith.

15 It is evident that the ends of a work piece project at each end a greater or less extent into the openings 10 of the respective dies, so that the dies have a shearing action thereon as the work piece is forced 20 downward therebetween. When the work piece has passed below the dies 9, it drops through registering openings 17 and 18 in the bolster plate 2 and bed 1 into any suitable receptacle provided therefor.

25 The dropping of work pieces from the magazine 11 into the guide way formed by the bars 12, and the successive delivery of work pieces through said guide way into 30 operative position over the die openings 10 is controlled by a slide 19, which is mounted for reciprocatory movements between the guide bars 12. This slide is of suitable length to close the lower end of the magazine 11, except when the slide is in complete 35 retracted position, thus permitting a work piece to drop into the guide way only in advance of said slide and when in retracted position.

The slide 19 has toggle link connection 40 to 20 with a shaft 21, journaled in suitable bearings 22 on top of the bolster plate 2, and carries a pinion 23 in mesh with the teeth of a vertically reciprocating rack-bar 24. This rack-bar has its upper end projected loosely through an arm 25 extended horizontally from the lower end portion of the ram 15, and is provided above and below said arm with stop collars 26 and 27, respectively, which are spaced to permit a 45 limited movement of the arm 25 with respect to the rack-bar. The arm 25 when moved upward with the ram 15, and near its upper position, is intended to engage the stop collar 26, which is suitably positioned 50 for such purpose, and to effect a raising of the rack-bar 24 during the balance of the upward movement of the ram, thereby effecting a forward movement of the slide 19 to place a workpiece *a*, which is disposed 55 in the guide way in advance thereof, in operative position over the die openings 10 and below the plunger 16. Upon the next downward movement of the ram 15, the rack-bar 24 lowers therewith by gravity and 60 causes a retraction of the slide 19 out of 65

register with the plunger 16. When the plunger 16 is near the limit of its downward stroke, the arm 25 engages the lower stop collar 27 and effects a positive lowering of the rack-bar and a complete retraction of the slide 19 to permit the lowermost work piece *a* in the magazine 11 to enter the guide way in advance of the slide. Upon the next upward movement of the plunger, the rack-bar 24 is raised and the 70 slide 19 operated to force the work piece *a*, disposed in advance thereof, into holding position between the flexible ends of the bars 12 and in register with the plunger 16 and die openings 10. 80

It is evident that I have provided a simple and efficient mechanism which is operable to successively feed work pieces into operative position above the broaching or trimming die and to force the work pieces down 85 between the dies to simultaneously trim or broach the ends thereof.

I wish it understood that my invention is not limited to any specific construction, arrangement, or form of the parts, as the present embodiment thereof is merely illustrative of one form of the invention and is capable of numerous modifications without departing from the spirit of the claims. 90

Having thus described my invention, 95 what I claim is new and desire to secure by Letters Patent is:—

1. In a machine of the class described, two transversely spaced dies, each die forming a V-shaped opening having cutting walls, and means for forcing a work piece between said dies with its ends projecting in the openings thereof to effect a simultaneous trimming of such ends. 100

2. In a machine of the class described, two transversely spaced dies, each die forming a V-shaped opening having cutting walls, and means for forcing a work piece between said dies with its ends projecting in the openings thereof to effect a simultaneous trimming of both ends, and means 110 periodically operable to automatically move work pieces into operative relation to said dies.

3. In a machine of the class described, two transversely spaced V-shaped dies, means for forcing a work piece between said dies to cause the dies to simultaneously trim the ends of the work piece, and means operable to periodically deliver a work 115 piece into position to be forced between the dies by said surface means, said delivery means having parts which frictionally engage and yieldingly hold a plunger and the work piece in operative relation to said 120 dies and first means.

4. In a machine of the class described, die means having transversely spaced dies provided with V-shaped work trimming openings, a plunger reciprocally movable 130

to force a work piece between said spaced die parts to simultaneously trim the ends of the work piece, a magazine, and means operable by movements of said plunger to periodically deliver work pieces from said magazine into position to be engaged by the plunger and forced between said die parts.

5. In a machine of the class described, a reciprocally movable plunger, die members 10 for coöperating with said plunger when moved in one direction to simultaneously trim the ends of a work piece, a magazine, a guide way leading from said magazine to a point between said plunger and die means, 15 a slide movable in said guide way, to successively deliver work from said magazine to operative position between said plunger and die means, a rack bar periodically movable by said plunger at predetermined

points in a movement thereof, and means 20 connecting said rack bar and slide operable to impart predetermined reciprocal movements to the slide from movements of said rack bar.

6. In a machine of the class described, 25 means operable to trim a work piece, guide bars forming a guide way which leads to said means from one side thereof, the forward ends of said bars being transversely yieldable and adapted to coöperate to frictionally grip a work piece therebetween in operative relation to said means, and means periodically operable to move a work piece in said guide way into operative position between the flexible ends of said guide bars. 30 35

In testimony whereof, I have hereunto signed my name to this specification.

AUGUSTUS F. DONALDSON.
